UNITED STATES PATENT OFFICE.

JAMES E. BRYAN, OF ST. PAUL, MINNESOTA.

DESIGN FOR A SHOW-CASE HOLDER AND REFLECTOR FOR ELECTRIC LAMPS.

45,147.

Specification for Design.

Patented Jan. 13, 1914.

Application filed November 3, 1913. Serial No. 799,039. Term of patent 7 years.

To all whom it may concern:

Be it known that I, JAMES E. BRYAN, a citizen of the United States, residing at St. Paul, in the county of Ramsey and State of Minnesota, have invented a new, original, and ornamental Design for Show-Case Holders and Reflectors for Electric Lamps, of which the following is a specification, reference being had to the accompanying drawing, forming part thereof.

In the drawings Figure 1 is a plan view

of a reflector showing my new design; Fig. 2 is a front elevation thereof; and Fig. 3 is a cross section on line α — α of Fig. 2.

I claim:

The ornamental design for a show case holder and reflector for electric lamps as shown.

JAMES E. BRYAN.
